ASSIGNEES TO STANDARD OIL COMPANY, OF SAN FRANCISCO, CALIFORNIA, A
CORPORATION OF CALIFORNIA.

SUCKER-ROD ATTACHMENT TO PREVENT SANDING UP OF WELL-PUMPS.

1,327,611.

Specification of Letters Patent. Patented Jan. 13, 1920.

Application filed March 10, 1919. Serial No. 281,738.

To all whom it may concern:

Be it known that we, ROBERT LEE BURNS and FRED FREAMOND WINGER, citizens of the United States, residing at Taft, in the 5 county of Kern and State of California, have invented certain new and useful Improvements in Sucker-Rod Attachments to Prevent Sanding Up of Well-Pumps, of which the following is a specification.

10 Our invention relates, in general, to oil and other well-pumps, and particularly to an attachment to the sucker-rods, the object of which is to automatically lift the pump plunger out of the working-barrel whenever sand enters the pump in sufficient 15 quantity to prevent its operation.

By thus lifting the plunger when beginning to sand up, the loss of a working barrel and parting of the rods are prevented.

20 Our invention consists in the novel attachment which we shall now fully describe by reference to the accompanying drawings in which we illustrate the preferred form of the device, it being understood, however, 25 that changes in form and structure may be made without departing from the spirit of our invention as set forth in our claims.

Figure 1 is an elevation of our attachment.

30 Fig. 2 is an elevation at right angles to Fig. 1.

Fig. 3 is a top plan enlarged of the operative portion of the attachment.

Fig. 4 is a vertical section partly in elevation enlarged of said operative portion.

1 is the body or stock of the attachment, which in practice is best in the form of a pair of steel reins. The top of the stock is provided with a T-head 2, by which it is 40 suspended from the walking-beam (not shown) or other source of reciprocative motion usually employed in the operation of well-pumps.

At the lower end, the stock is formed with 45 a tubular foot 3 split in the plane of its axis and adapted to receive the ratchet bar 4 which passes axially through it.

In the foot 3 are mounted the pawls or dogs 5, pivoted at 6 and controlled by a 50 spring 7 acting through a collar 8 resting on the pawls. The relation of these pawls to the ratchet-teeth of the bar 4 is such as shown in Fig. 4 that the bar may move up-

ward relatively to the foot 3, the teeth of the bar then slipping the pawls, but not 55 downward, since in this direction the ratchet teeth and pawls positively engage, and the pawls themselves rest on the base flange 9 of the foot 3.

10 is a clamp which embraces the split- 60 foot 3, being secured to one half by the cap screws 11, and engaging the other half through a tightening screw 12.

By loosening the clamp 10 the halves of the foot 3 may separate to allow the ratchet- 65 bar 4 to be moved downward, for setting it when desired.

The lower end of the ratchet bar 4 is adapted for connection as indicated at 13 by means of any customary or suitable 70 coupling with the sucker-rod string extending to the pump-plunger.

The operation of the device is as follows:

The attachment is suspended from the walking beam or other source of reciprocative motion, by means of the T-head 2 of the reins 1. The lower end of the ratchet bar 4 is made fast at 13 to the sucker-rods, and then the walking beam is set in motion. As long as the pump works normally the 80 ratchet bar 4 is held against the pawls 5 by the weight of the rods, on both the up and down strokes, and does not change its position relatively to the foot 3 nor to the walking beam. But as soon as the pump begins 85 to sand up, the sucker-rods vary their stroke being then supported and limited by the sand in the working barrel of the pump, with the result that on the down stroke, the rods and the ratchet bar 4 remain stationary, 90 while the foot 3 of the reins 1 drops along the bar the length of the pump stroke, the pawls slipping the ratchet-teeth of the bar. But at the end of the down stroke the pawls catch the bar lower down and upon the up 95 stroke they lift it, together with the sucker-rods, so that the pump-plunger is raised out of the barrel. This condition continues until the plunger is clear of the sand.

We claim:

1. A sucker-rod attachment for the described purpose comprising a stock adapted for suspension from a source of reciprocative motion, said stock having a tubular split foot; a pawl pivoted and housed within said 105 foot; a ratchet bar adapted for connection

with the sucker-rod, said bar being fitted through said foot for relative linear movement therein, the ratchet teeth of said bar positively engaging the pawl on the upward 5 stroke of the stock and slipping it in the reverse direction; and a regulatable clamp embracing said foot, whereby the ratchet bar may be adjusted therein.

2. A sucker-rod attachment for the described purpose comprising a stock adapted 10 for suspension from a source of reciprocative motion, said stock having a tubular split foot with an inwardly extending base flange; a pair of oppositely disposed pawls housed within said foot, said pawls being pivoted in the side walls of the foot and resting normally on its base-flange; a collar housed within the foot and resting on the pawls; a spring housed within the foot and

bearing on the collar; a ratchet-bar adapted 20 for connection with the sucker-rod, said bar being fitted through the foot of the stock for relative movement therein, the ratchet teeth of said bar positively engaging both pawls on the upward stroke of the stock and slipping them in the reverse direction, and a regulatable clamp embracing said split foot, whereby the ratchet bar may be adjusted therein.

25 In testimony whereof we have signed our names to this specification in the presence of two subscribing witnesses.

ROBERT LEE BURNS.

FRED FREAMOND WINGER.

Correction in Letters Patent No. 1,327,611.

It is hereby certified that Letters Patent No. 1,327,611, granted January 13, 1920, upon the application of Robert Lee Burns and Fred Fremond Winger, of Taft, California, for an improvement in "Sucker-Rod Attachments to Prevent Sanding Up of Well-Pumps," were erroneously issued to Standard Oil Company, as assignee of the entire interest in said invention, whereas said Letters Patent should have been issued to the inventors, said Burns and Winger, as sole owners of said invention; and that the said Letters Patent should be read with this correction therein that the same may conform to the record of the case in the Patent Office.

Signed and sealed this 10th day of February, A. D., 1920,
